UNITED STATES PATENT OFFICE.

JAMES SMITH, DECEASED, LATE OF DORMONT BOROUGH, PENNSYLVANIA; BY ISABELLA K. SMITH, ADMINISTRATRIX, OF DORMONT BOROUGH, PENNSYLVANIA, ASSIGNOR TO ISABELLA K. SMITH, OF DORMONT, PENNSYLVANIA.

PROCESS AND APPARATUS FOR CASTING FURNACE BOSH PLATES.

Application filed January 29, 1925. Serial No. 5,658.

To all whom it may concern:

Be it known that JAMES SMITH, deceased, late a citizen of the United States of America, and a resident of the borough of 5 Dormont, in the county of Allegheny and State of Pennsylvania, did invent a new and Improved Process and Apparatus for Casting Furnace Bosh Plates, of which the following is a specification.

10 The invention consists in a new and improved process and apparatus for casting furnace bosh-plates in an upright position and without embedded anchors.

When, as has been the common practice, 15 bosh-plates are cast in a horizontal position, the horizontally disposed core must be supported in place by means of metal anchors or chaplets which remain embedded in the casting and weaken the same, frequently resulting in leaks or ruptures.

In Letters Patent of the United States, No. 1,438,271, issued on December 12, 1922, to the said James Smith, now deceased, a process and apparatus are disclosed for casting bosh-plates in a vertical position but with the nose of the plate at the top and its butt at the bottom, the core being supported from below by a sand base. The result is that the best portion of the casting and the 20 purest metal is in the butt of the plate, while its nose, which is to be exposed to the greatest heat and wear, is formed of the poorest portion of the casting.

In the improved process herein described, 25 the bosh-plates are cast in a vertical position, but with their noses down, so that the purest metal and therefore the best portion of the casting forms the nose of the plate while the poorer metal goes to form the butt.

30 Herein is disclosed new and improved apparatus whereby the new and improved process may be successfully and commercially worked.

In the accompanying drawings, which 35 are however merely intended to illustrate the principles of the invention without limiting the scope thereof to the structures shown, Fig. 1 is a vertical section taken along the line I—I in Fig. 2 showing the mold and core assembled in the flask ready for pouring; Fig. 2 is a section along the line II—II in Fig. 1, also showing the pouring sprue; Fig. 3 is an enlarged detail of parts shown also in Fig. 1; Fig. 4 is a plan

view of the core-box used to form the sand core; Fig. 5 is a vertical section illustrating the operation of forming the cheek-mold in an inverted position, showing the cheek, the pattern and the sprue pattern assembled on the follow board and the molder's sand rammed about the same; Fig. 6 is a similar view showing the drag inverted and placed on the cheek, the sand rammed in the drag to form the drag-mold and the bottom board placed thereon; Fig. 7 shows the assembled cheek and drag, with their contents, reverted on the bottom board and the follow board removed; Fig. 8 shows the cope superimposed on the cheek for the step of forming the cope-mold; Fig. 9 shows the cope and 55 cope-mold lifted off the cheek and cheek-mold and set aside on trestles; Fig. 10 shows the cheek-mold lifted off the drag-mold and set on trestles and the sand core 60 set down into the cheek-mold; Fig. 11 is a similar view with the cope-mold in place on the cheek mold; Fig. 12 is a top plan view of the drag-mold showing the pouring gates which connect with the lower end of the sprue; Fig. 13 is a horizontal section taken along the line XIII—XIII in Fig. 11, and Fig. 14 is a perspective of a conventional type of bosh-plate which is 65 shown for the sake of clearness in description.

The molding flask, which is shown in Fig. 1 assembled ready for pouring, is comprised of the drag A containing the drag-mold A'; the cheek B containing the cheek-mold B'; and the cope C containing the cope-mold C'. D represents the sand core suspended from above from the cheek-mold. E represents the sprue which connects at its lower end with the horizontal gates F formed in the top of the drag-mold and connected to the 70 mold cavity at its opposite narrower sides, as best shown in Fig. 12.

The drag, cheek and cope are detachably connected together by the pins 1 which engage the pierced ears 2. When the mold is ready for pouring the entire flask is clamped together in the usual manner.

The core D is suspended in place by the cross plates 3 whose ends rest on the top of the cheek-mold and whose centers are provided with circular holes in which are fixed the lengths of pipes 4 held in place by the upper and lower lock nuts 5. The under

surface of the cope mold is provided with suitable recesses 6 to provide clearance for the plates 3 and the upper ends of the pipes 4. The lower ends of the pipes 4 extend 5 down into and are embedded in the sand of the core D. The exposed portions of the pipes 4 below the plates 3 and the lower lock nuts 5 are wrapped with asbestos tape, as shown at 7, to prevent the molten metal 10 adhering thereto, and the lower surfaces of the plates 3 are covered with asbestos paper for the same purpose.

The wrapped portions of the pipes 4 form the end water ports 4^a, see Fig. 14, of the 15 finished bosh-plate. At the center of the core-butt a third length of pipe 8 is provided having its lower end embedded in the sand of the core and its exposed portion being wrapped with asbestos tape 7 to prevent 20 the metal adhering thereto. The under surface of the cope-mold is recessed to give clearance for the upper end of the pipe 8. The wrapped portion of the pipe forms the central water port 8^a of the finished bosh-plate, as shown in Fig. 14.

The embedded ends of the pipes 4 and 8 are perforated, as shown in Fig. 8, to provide for the escape of the gases from the sand core, and the cope-mold is provided 30 with vent passages 9 connecting the upper ends of the pipes 4 and 8 to atmosphere to carry off said gases. 10 represents wires extending down through said pipes and embedded in the sand of the core to reinforce 35 the latter, said wires being bent substantially as shown. Other wires 11 are also embedded in the core intersecting the cavities in which are formed the cross partitions of the bosh-plate. The intersecting or adjacent 40 portions of said wires may be tied together by light wire which may be easily broken when the wires 10 are withdrawn from the cast plate.

The cope-mold has embedded in its lower 45 surface two hard sand blocks G which are provided with the substantially inverted U-shaped passages 12 whose ends are open to receive the molten metal to form the handles 12^a of the bosh-plate, as shown in Fig. 50 14. The tops of said passages 12 are connected by riser passages 13 with atmosphere, so that metal may completely fill the passages 12 to form the handles 12^a, and may rise up into view to indicate that the mold 55 has been filled. Also dross and impurities may thus escape through said risers.

14 represents temporary spacers, preferably formed by bending up a strip of sheet metal to substantially M-shape and inserting 60 them at either side of the core between it and the cheek-mold near the lower end of the latter. These spacers serve to properly center the core and hold it in position, thus insuring walls of uniform thickness for 65 the bosh-plate. These spacers are formed of

metal which will quickly and completely melt when reached by and immersed in the molten metal, and which will become amalgamated with the metal of the plate without impairing its quality. Thus, said spacers 70 may be made of thin sheet copper.

The upper end of the sprue E is provided with a pouring cup 15. Riser cups 15^a are also placed at the upper ends of the riser-passages 13.

The metal is poured down through the sprue E and passes horizontally through the gates F into the mold cavity, first filling the lower portion of the cavity and thus forming the nose of the plate, and then flowing 80 upwardly, melting and amalgamating with it the temporary spacers 14. When the metal comes to the surface through the riser passages 13, it indicates that the mold is full. When the metal has set the bosh-plate 85 is removed from the mold and the pipes 4 and 8, and the wires 10 removed, the sand removed from the interior of the plate, the metal which has hardened in the gates and risers cut off, and the ports 4^a and 8^a are 90 threaded for pipe connections.

It is evident that the best portion of the casting forms the nose of the plate where the greatest heat is to be resisted. This has been impossible of accomplishment by any 95 previous method of casting bosh plates.

There is a decided advantage in introducing the molten metal horizontally at the ends of the core instead of at the sides of the latter. The core is much less likely to 100 be displaced by this method of introducing the metal into the mold cavity. When the incoming metal impinges against the extended sides of the core it is almost impossible to prevent lateral shifting of the latter unless permanent supports, such as anchors or 105 chaplets are used. Again, the introduction of the metal at the ends of the core insures a better distribution and equal flow of the metal.

There is a further advantage in introducing the metal at a level above the bottom or nose of the mold cavity. As the metal first 115 fills up the portion of the mold cavity contained in the drag, it acts as a means for holding the core in its proper alignment, due to the upward rise of the metal, and when the rising level of the metal reaches and engulfs the temporary spacers, the latter have served their purpose and are melted 120 by and amalgamated with the poured metal.

The following is the method of preparing and assembling the mold for casting.

The core D is formed by ramming core 125 sand into the core box D' which is integral with the board H. The box is provided with a nose wall 16, side walls 17 and butt wall 18, the side walls preferably diverging toward the butt wall to conform to the radius 130

of the furnace bosh. The core box is also provided with partitions 19 to form the core cavities for the internal baffles 19^a of the bosh-plate, as shown in dotted lines in Fig. 5 14. It will be understood that the partitions 19 may be of any suitable character and positioned in any desired manner, depending upon the particular design of bosh-plate which is to be cast.

10 The butt wall 18 of the core box is provided with end channels 20 and an intermediate channel 20^a to receive the core pipes 4 and 8. The channels 20 are shallower at their outer extremity, as indicated by the 15 shoulder 20^b, and, after a bottom layer of sand is placed in the box, the wrapped pipes 4 are laid therein with their lower lock nuts 5 bearing outwardly against said shoulders, the inner and deeper portions of the channels 20 providing room for the lower lock nuts 5 and the asbestos wrapping 7, thus providing 25 convenient means for properly positioning the pipes 4 in the core box. The wrapped pipe 8 is also positioned in the intermediate channel 20^a. The wires 10 are placed in position with their outer ends extending through the pipes 4 and 8. The interior wires 11 are also placed in position. The partitions 19 are apertured as shown to accommodate the wires.

30 The core box is now filled with sand and rammed. The sand is then struck off flush with the top of the core box and a core plate put in place and clamped to the box, and 35 the whole inverted. The clamps are then removed and the box rapped to free the core and the box lifted off. The core is then sprayed and baked.

35 The cheek B is inverted and placed on the follow board I and the pattern J mounted thereon. The sprue form E' is then stepped into a socket in the follow board. The sand is now filled in and rammed, thus forming the cheek-mold B'. This step is illustrated 45 in Fig. 5. Referring now to Fig. 6, the drag A is now inverted and placed on the cheek B and the sand filled in and rammed, parting sand being used to separate the molds. The bottom board K is now placed 50 on the drag A, and the parts are clamped together and the whole reverted into the position shown in Fig. 7 and the follow board removed.

55 The cope C is placed on the cheek B, as shown in Fig. 8. The sprue pattern E' is drawn upward until its top is level with the top of the cope. The previously prepared sand blocks G are placed in position on the top of the pattern J. The print-forms 3^a and 8^b are positioned on the pattern J to form the recesses to receive the plates 3 and the upper ends of the pipes 4 and 8. A parting is made and the sand is now filled in and rammed to form the cope-mold C'.

60 The cope and its mold is then removed

and the pattern J is withdrawn, and the cheek and its mold lifted from the drag and set on trestles, as shown in Fig. 10. The plates 3 are now placed in position on the pipes 4 and the upper lock nuts 5 are put in place. The core D is then placed down in the cheek mold, as shown in Fig. 10, being supported from above by means of the cross-plates 3 which span the cheek mold as shown. The temporary spacers 14 are then inserted up between the core D and the cheek mold B'. The gates F are cut in the top surface of the drag mold A', as shown in Fig. 12. The cope C and its mold C' are replaced on the cheek B and its mold B', as shown in Fig. 11. The vent passages 9 and the riser passages 13 have been previously formed in the cope-mold C'. The cheek and cope are then placed on the drag and all clamped thereto, and the mold is ready for pouring.

75 The foregoing description is of hand molding but it will be understood by those skilled in the art that molding machines may be employed in the process for preparing the mold.

The claims:

1. The process of casting a furnace bosh-plate, nose downwardly and in a vertically disposed position in a mold wherein the core 85 is suspended from above, which consists in admitting the metal into the mold cavity surrounding the mold at a level above but near the lower end of the cavity, so that the molten metal first flows downwardly from the admission level to form the nose of the plate which metal in setting anchors the core in position, and the subsequently admitted metal flows upwardly within the cavity to form the remainder of the plate. 105

2. The process of casting furnace bosh-plates, nose downwardly and in a vertically disposed position in a mold wherein the core is suspended from above, which consists in admitting the metal into the mold cavity surrounding the core at the opposite narrower sides of the core and at a level above but near the lower end of the core, so that the metal first flows downwardly from the admission level to form the nose of the plate which metal in setting anchors the core in position, and the subsequently admitted metal flows upwardly within the cavity to form the remainder of the plate. 115

3. The process of casting furnace bosh-plates, nose downwardly and in a vertically disposed position in a mold wherein the core is suspended from above, which consists in interposing between the broader sides of the core and the adjacent mold walls temporary 125 spacers, and admitting the metal at the narrower sides of the core at a level near but above the lower end of the core so that the molten metal first admitted flows downwardly in the cavity surrounding the core

- to form the nose of the plate and said metal in setting anchors the core in position and the subsequently admitted metal flows upwardly within the mold cavity and forms the remainder of the plate.
4. The process of casting furnace bosh-plates, nose downwardly and in a vertically disposed position in a mold wherein the core is suspended from above, which consists in interposing between the broader sides of the core and the adjacent mold walls temporary spacers, and admitting the metal at the narrower sides of the core at a level near but above the lower end of the core so that the molten metal first admitted flows downwardly in the cavity surrounding the core to form the nose of the plate and said metal in setting anchors the core in position and the subsequently admitted metal flows upwardly within the mold cavity and forms the remainder of the plate, the spacers being of suitable material so that they are melted by the rising metal and become amalgamated in the plate.
5. The process of casting a furnace bosh-plate, nose downwardly, in a vertically disposed position, in a mold containing a core suspended from above, which consists in interposing between the sides of the core and the mold walls temporary spacers meltable by the molten metal; and introducing the molten metal at both narrower sides of the core.
6. The process of casting a furnace bosh-plate, nose downwardly, in a vertically disposed position, in a mold containing a core suspended from above, which consists in interposing between the sides of the core and the mold walls temporary spacers meltable by the molten metal, introducing the molten metal at both narrower sides of the core, and a level slightly above the lower extremity of the core whereby the nose of the plate is first cast and the metal in setting forms a centering support for the core.
7. The process of casting a furnace bosh-plate, nose downwardly, in a vertically disposed position, in a mold containing a core suspended from above, which consists in introducing the molten metal into the mold at the narrower sides of the core and slightly above the lower extremity of the latter, whereby the nose of the bosh-plate is first formed and the metal in setting forms a centering support for the core.
8. In means for casting furnace-bosh plates, nose downwardly and in a vertically disposed position, the combination of a mold, a core suspended from above in the mold cavity, and pouring gates leading into the mold cavity opposite to both the narrower sides of the core.
9. In means for casting furnace-bosh plates, nose downwardly and in a vertically disposed position, the combination of a mold, a core suspended from above in the mold cavity, and pouring gates leading into the mold cavity opposite to both the narrower sides of the core, said gates being above but near the lower end of the core.
10. In means for casting furnace-bosh plates, nose downwardly and in a vertically disposed position, the combination of a mold, a core suspended from above in the mold cavity, pouring gates leading into the mold cavity opposite to both the narrower sides of the core, and temporary spacers interposed between the broader sides of the core and the walls of the mold cavity.
11. In means for casting furnace-bosh plates, nose downwardly and in a vertically disposed position, the combination of a mold, a core suspended from above in the mold cavity, pouring gates leading into the mold cavity opposite to both the narrower sides of the core, and temporary spacers interposed between the broader sides of the core and the walls of the mold cavity, said spacers being of suitable material so as to be melted by and amalgamated with the molten metal.
12. In means for casting anchorless bosh-plates in a vertical position comprising a mold, a core suspended from above in said mold, and means for introducing the molten metal into the lower portion of the mold at a level slightly above the lower extremity of the core and at both narrower sides thereof.
13. In means for casting anchorless bosh-plates in a vertical position comprising a mold, a core suspended from above in said mold, means for introducing the molten metal into the lower portion of the mold at a level slightly above the lower extremity of the core and at both narrower sides thereof, and temporary spacers interposed between the sides of the core and the walls of the mold above the level of the entrance of the molten metal.
14. In means for casting anchorless bosh-plates in a vertical position comprising a mold, a core suspended from above in said mold, means for introducing the molten metal into the lower portion of the mold at a level slightly above the lower extremity of the core and at both narrower sides thereof, and temporary spacers interposed between the sides of the core and the walls of the mold above the level of the entrance of the molten metal, said spacers being of material adapted to be melted by the metal and to be amalgamated therewith.
15. In means for casting furnace bosh-plates in a vertically disposed position and nose-downwardly comprising a mold having a cavity corresponding to the outer conformation of the bosh-plate to be formed, a core suspended from above within said cavity, and gates for the admission of metal opening into the lower portion of said cavity.

- and above the lower extremity of said core, said gates being formed in the two narrower vertical walls of said cavity adjacent to the narrower sides of said core.
- 5 16. In means for casting furnace bosh-plates in a vertically disposed position and nose-downwardly comprising a mold having a cavity corresponding to the outer con-formation of the bosh-plate to be formed, a core suspended from above within said cavity, gates for the admission of metal opening into the lower portion of said cavity and above the lower extremity of said core, said gates being formed in the two narrower vertical walls of said cavity adjacent to the narrower sides of said core, and temporary spacers interposed between the core and the walls of the cavity above the level of the gates.
- 10 17. In means for casting furnace bosh-plates in a vertically disposed position and

nose-downwardly comprising a mold having a cavity corresponding to the outer con-formation of the bosh-plate to be formed, a core suspended from above within said cavity, gates for the admission of metal opening into the lower portion of said cavity and above the lower extremity of said core, said gates being formed in the two narrower vertical walls of said cavity adjacent to the narrower sides of said core, and temporary spacers interposed between the core and the walls of the cavity above the level of the gates, said spacers being composed of ma-terial which is melted and incorporated in the molten metal as the latter engulfs said spacers.

Signed at Pittsburgh, Pa., this 17th day of January, 1925.
